UNITED STATES PATENT OFFICE.

HENRY J. FRIEDMAN, OF CLEVELAND HEIGHTS, OHIO.

DENTAL CONNECTION.

1,413,847.

Specification of Letters Patent. Patented Apr. 25, 1922.

Application filed May 19, 1921. Serial No. 470,873.

To all whom it may concern:

Be it known that I, HENRY J. FRIEDMAN, a citizen of the United States, residing at Cleveland Heights, county of Cuyahoga, and State of Ohio, have invented a new and useful Dental Connection, of which the following is a specification.

My invention relates to connecting means particularly applicable in dentistry and 10 similar purposes.

The object of my invention is to provide an improved connection between two objects whereby one of the objects may have certain movement or play in all directions and within 15 in certain limits in relation to the other object and whereby the objects can be connected or disconnected readily and which connecting means requires the least possible space.

20 In many instances it is necessary that two objects shall be held in such relation to each other that one of the objects can move in different directions in relation to the other object, for instance in dentistry where it is 25 necessary to hold a denture (an artificial tooth for instance) to a natural tooth without causing any binding or other inconvenient feeling in the mouth, or preventing the denture from binding due to expansion or 30 contraction due to change of temperature in the mouth while eating or drinking for instance, or preventing the denture from moving in any direction, within limits, due to uneven pressure brought against the denture 35 either downward or sidewise, but permitting the denture to be readily removed from the mouth for the purpose of inspection or cleaning and to be readily inserted in the mouth.

The present invention is illustrated in the 40 accompanying drawing in which Fig. 1 is a general side view of a connection between a natural tooth and a portion of a denture; Fig. 2 is a section on line 2 of Fig. 1; Fig. 3 is a section on line 3 of Fig. 2; Fig. 4 is a 45 section on line 4 of Fig. 3; Fig. 5 is a sectional plan view (similar to Fig. 2) showing a modification; and Fig. 6 is a section on line 6 of Fig. 5.

Similar reference characters refer to similar parts throughout the views.

Referring now particularly to Figs. 1, 2, 3, and 4 where the denture A is to be held to the natural tooth B.

The natural tooth B is supposed to be in

normal condition in the gum while the denture A is to be held thereto in such a manner that the same may move in all directions and at the same time be prevented from detaching itself and be readily inserted into or removed from the mouth.

60 The connection mechanism shown here consists of the clasp C, the bracket D, and the guide E.

65 The clasp C may be made of any material suitable for the purpose and is formed with the band 10 extending part way around the tooth B and with the projection or clip 11 extending part way over the top of the tooth B. For the purpose of better security of the clasp to the tooth and better insertion or removal facility, the clasp 10 may be made of material which has the nature of a spring so that the clasp may automatically attach or detach itself to or from the tooth B in a 70 satisfactory manner; the composition of this material however must not be injurious to the human system. The form of the ends of the band 10 and the clip 11 should be made to conform to the tooth B and made smooth to prevent injury to the tongue or interior 75 of the mouth.

80 The bracket D may be made of any material suitable for the purpose and is formed with the wall 12, the sides 13 and 14 bent down from the wall 12 and of substantially 85 equal lengths, and the lug 15 bent down from the wall 12, at the bottom thereof and substantially midway between the sides 13 and 14 and extending in the same direction and approximately the same distance as the sides 13 and 14. The free ends of the sides 13 and 14 and of the lug 15 are, preferably, fitted and soldered to the clasp at 16 as shown. This bracket may however be secured to the clasp in any other manner or 90 may be made integral therewith.

95 The guide E may be made of any suitable material and is formed with the opening 17 somewhat wider than the width of the lug 15, and with the foot 18 which, in this instance, is secured to the guide by soldering or other suitable means and is bent and formed to suit the portion 19 of the denture and is intended to be imbedded therein. The upper portion of the foot 18 serves as a closure of the bottom of the opening 17. The entire guide E may also be made of one piece 100 of material without detracting from its effi- 105

ciency except when assembling the attachment as a whole. The width of the top portion 20 of the guide E is less than the distance between the inside of the sides 13 and 14, and the thickness thereof is approximately one half of the inside length of the sides 13 and 14.

After the parts C, D, and E are made up as units, they may be assembled as follows:

- 10 Place the guide E in the bracket D with the lug 15 projecting through the opening 17 in the guide E, then solder the three ends of the sides and the lug to the clasp C at 16 as shown, then imbed the foot 18 in the denture and secure the artificial tooth 21 to the portion 19 in any suitable or approved manner well known in dentistry or otherwise.

The guide E is now connected to the denture and to the bracket D and to the clasp C and the connecting mechanism as a whole permits the denture to move in any direction in relation to the clasp C due to the clearances between all of the connecting parts.

In practice, this dental connection operates as follows: The tooth B is supposed to be naturally rooted in the gum. The denture, now assembled as set forth, has the clasp C attached. The denture is now placed in the mouth with the clasp C over the tooth B and pressed down until the clasp C engages the tooth B as desired at which stage the denture is in normal position and adapted to be moved in any direction due to the clearances between all of the connecting parts. Whenever an unequal down or side pressure is brought upon the teeth, as in mastication food for instance, the gums, jaw-bone and other human structures take care of such inequality in natural teeth, but in a fixed denture it would prove disastrous. When such unequal pressure is brought upon a denture provided with this invention, the probability of disastrous results is eliminated. For instance, when a certain pressure is brought upon the tooth B and a greater pressure is brought upon the tooth 21, either downward or sidewise, the tooth 21 can move up or down or from side to side or from front to rear due to the clearances between all connecting parts and the denture will not be injured. The slot 17 has more up and down than side clearance in order to permit of placing a liner under the portion 18 in case the gums shrink, or filing off the portion 18 in case the gums swell, or providing a means to properly adjust the denture either when it is first fitted or when later adjustment is necessary.

When the foot 18 is made separate and secured to the guide, the bracket D may be made integral with the clasp C and the foot 18 is then secured to the guide E after the same is inserted in its position over the lug 15. This arrangement eliminates a joint 65 between the clasp and the bracket and per-

mits of quantity production of the separate parts and ready assemblage thereof when installing a denture.

Referring now to Figs. 5 and 6 which show a modification comprising the clasp 70 F substantially the same as the clasp C, the bracket G, and the guide H.

The bracket G has the wall 22 and sides 23 and 24 similar to the wall 12 and sides 13 and 14, and also has the cylindrical projection 25 which extends to and is secured to the clasp F as are also the sides 23 and 24, similar to the sides 13 and 14.

The guide H has the circular opening 26, larger in diameter than the projection 25 to 80 permit free movement between the bracket G and the guide H for the purposes previously set forth.

All other features of this modification being similar to those previously set forth. 85

It will be seen that the present invention provides an efficient and economical means for attaching or detaching a denture, and providing adjustment thereof, and permitting movement thereof in all directions, and 90 eliminating binding or other inconveniences found in connection with the usual denture.

I claim:

1. A dental connection comprising a clasp provided with a pocket and adapted to engage a natural tooth, a guide having one end thereof loosely fitting into said pocket and the other end thereof adapted to be embedded in a denture. 95

2. A dental connection comprising a clasp provided with a pocket and a lug projecting therein and adapted to engage a natural tooth, and a guide having one end thereof adapted to be embedded in a denture and the other end thereof loosely fitting into said 100 pocket and over said lug.

3. A dental connection comprising a clasp adapted to engage a natural tooth and provided with an opening and with a lug extending across this opening, and a guide having one end thereof adapted to be embedded in a denture and the other end thereof fitting loosely into said opening and over 110 said lug.

4. An apparatus of the character described comprising a clasp adapted to engage a support, a bracket on said clasp and provided with a lug and two side walls, and a guide in said bracket and over said lug and provided with an opening larger than said lug 120 and the upper portion thereof narrower than the distance between said two side walls.

5. An apparatus of the character described comprising a clasp adapted to engage a support, a bracket on said clasp and provided with a lug and two side walls, and a guide in said bracket and over said lug and provided with an opening larger than said lug and the upper portion thereof narrower than the distance between said two side 130

walls and the lower portion thereof adapted to be secured to an article which is to be connected to said support.

6. In a dental apparatus of the character described, the combination of a natural tooth and a denture, with a connecting mechanism between said natural tooth and said denture, which connecting mechanism comprises a

clasp adapted to engage or disengage said tooth and provided with an opening and 10 with a lug extending across this opening, and a guide having its lower end embedded in said denture and its upper end operating loosely in said opening and provided with a slot operating loosely over said lug.

HENRY J. FRIEDMAN.
